UNITED STATES PATENT OFFICE.

IRA I. SIDES, OF GREELEY, COLORADO.

COMBINED RULER AND BLOTTER.

No. 827,574.

Specification of Letters Patent.

Patented July 31, 1906.

Application filed March 19, 1906. Serial No. 306,863.

To all whom it may concern:

Be it known that I, IRA I. SIDES, a citizen of the United States, residing at Greeley, in the county of Weld and State of Colorado, 5 have invented a new and useful Combined Ruler and Blotter, of which the following is a specification.

This invention relates to an article of stationery; and the principal object is to provide 10 a novel, simple, and useful article of manufacture that is capable of being employed in a variety of ways and for a number of different purposes.

Referring to the accompanying drawings, 15 Figure 1 is a plan view of one embodiment of the invention. Fig. 2 is a longitudinal sectional view through the same. Fig. 3 is a cross-sectional view. Fig. 4 is a plan view of a modified form of construction. Fig. 5 is a 20 detail sectional view therethrough. Fig. 6 is still another embodiment of the invention, showing different means for fastening the blotter to the body. Fig. 7 is a detail sectional view therethrough. Fig. 8 is a detail 25 plan view illustrating still another form of fastener, and Fig. 9 is a detail sectional view therethrough.

Similar reference-numerals designate corresponding parts in all the figures of the 30 drawings.

Referring to the embodiment illustrated in the first three figures, a ruler is employed that is in the form of a body 10, composed of sheet material of any desired character, said 35 body having opposite longitudinal and parallel edges 11 and 12. The edge 12 is shorter than the edge 11. One of the end edges of the body comprises straight portions 13 and 14, disposed in angular relation, the portion 40 14 being located at an acute angle to the edge 11 and the portion 13 being disposed at an obtuse angle to the longitudinal edge 12. As a result a pointed corner 15 is formed at one end of the body. The other end edge comprises a portion 16, disposed at right angles to the edge 11, and a curved portion 17, which is 45 offset from the portion 16 and connects with the other edge 12, forming a point 18. The margins inside said various edges are provided 50 with scales 19, conforming to the said edges. Upon the upper or exposed face of the body and in the upper portion thereof is placed a calendar, (designated by the reference-number 20.) An open space 21 is left below 55 this calendar, in which suitable advertising may be printed or otherwise placed.

Secured to the under side of the body is a blotter 22, which terminates short of the various edges above described and is held in place by any suitable means. For instance, 60 if the body is made of metal or other bendable material, lips 23 may be cut from the material of the body and engage over the edges of the blotter, as shown. Instead of this structure wire staples 24 may be employed, which, 65 as shown in Figs. 6 and 7, are passed through the body 10 and through the blotter-pad 22, or, if it is desired, pronged headed fasteners 25 may be employed, which, as illustrated in Figs. 8 and 9, are passed through the body 10 70 and the blotter 22.

The structure may be employed in a number of ways. By having the edges disposed at different angles about the body a number of angles can be drawn. Furthermore, the 75 sharp corners permit the ruling of lines in confined places, such as on the pages of books contiguous to the binding. The blotter may be made to perform its ordinary functions, but, furthermore, supports the body above the 80 surface and provides overhanging ruling edges, as will be apparent. In this latter connection not only are the ruling edges provided, but the blotter located inside the same will absorb any ink that may flow in from 85 such edges and which would otherwise blot the ruled surface.

The structure disclosed in Figs. 4 and 5 has substantially the same characteristics as the embodiment already set forth. A body 10^a is 90 employed having parallel longitudinal edges 11^a and an end edge consisting of angularly-disposed portions 12^a and 13^a. The other end edge has a portion 14^a disposed at right angles to one of the longitudinal edges 95 15^a and a curved portion 17^a coacting with the other longitudinal edge. Scales 16^a extend around the margins of the body, and a calendar 17^a may be located in the upper portion thereof, leaving a space 18^a, on which advertising matter may be displayed. The blotter 19^a is held in place on the under side of the body by lips 20^a, cut from the material of the body and passed through openings 21^a in the blotter, as illustrated in Fig. 5. 105

The advantages of my invention will be apparent when it is explained that by its use the bookkeeper has before him a calendar, a ruler, a blotter, all in one, the article being flexible, so as to conform to the curvature of the writing-page. The straight portion 16 enables a bookkeeper to rule up his ledger 110

without moving the rule. Indeed he can rule the book at almost any angle by using the different edges of the body. The projecting-point 18 can be used as a letter-opener.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is—

1. In a device of the class described, a ruler having substantially parallel longitudinal edges extending from end to end, and an end edge comprising portions arranged end to end and disposed in angular relation to each other, one of said portions being disposed at an acute angle to one of the longitudinal edges, the other portion being located at an obtuse angle to the other edge.

2. A blotter comprising a body having parallel longitudinal straight edges, and an end edge at one end of the body having portions located at different angles, and an end edge at the other end of the body having a curved portion, and scales located along the

margin of the body and coacting with the said edges thereof.

3. In a device of the class described, a flexible ruler having its body provided with continuous longitudinal straight edges extending from end to end, and an end edge having portions thereof disposed at different angles to each other and to the longitudinal edges.

4. In a device of the class described, a ruler having its body provided with continuous longitudinal straight edges extending from end to end, and end edges, each of said end edges comprising portions located in angular relation to each other, said portions being disposed at different angles to the longitudinal edges.

5. In a device of the class described, the ruler having its body provided with longitudinal straight edges, and an end edge provided with a straight portion extending from one of the longitudinal edges and a curved portion terminating in a point at the other longitudinal edge, the inner end of the curved portion being located outside the inner end of the straight portion.

In testimony that I claim the foregoing as my own I have hereto affixed my signature in the presence of two witnesses.

IRA I. SIDES.
